US0D1038119S

(12) **United States Design Patent** (10) Patent No.: **US D1,038,119 S**
(45) Date of Patent: ** Aug. 6, 2024

(54) **WATCH**

(71) Applicants: **Zepp, Inc.**, Cupertino, CA (US); **Anhui Huami Health Technology Co., Ltd.**, Hefei, Anhui FTZ (CN)

(72) Inventors: **Wei Po Chao**, Cupertino, CA (US); **Luying Cao**, Hefei (CN)

(73) Assignees: **Zepp, Inc.**, Cupertino, CA (US); **Anhui Huami Health Technology Co., Ltd.**, Anhui FTZ (CN)

(**) Term: **15 Years**

(21) Appl. No.: **35/517,351**

(22) Filed: **Jun. 1, 2022**

(80) **Hague Agreement Data**

Int. Filing Date: **Jun. 1, 2022**

Int. Reg. No.: **DM/221577**

Int. Reg. Date: **Jun. 1, 2022**

Int. Reg. Pub. Date: **Jun. 2, 2023**

(51) **LOC (14) Cl.** **14-02**

(52) **U.S. Cl.**

USPC **D14/344**
